UNITED STATES PATENT OFFICE.

GORHAM GRAY, OF BOSTON, MASSACHUSETTS, ASSIGNOR TO THE SPIRAL WIRE COMPANY, OF PORTLAND, MAINE.

ELECTRICAL CONDUCTOR.

SPECIFICATION forming part of Letters Patent No. 543,960, dated August 6, 1895.

Application filed December 14, 1894. Serial No. 531,791. (No model.)

To all whom it may concern:

Be it known that I, GORHAM GRAY, a citizen of the United States, and a resident of Boston, in the county of Suffolk and State of Massachusetts, have invented certain new and useful Improvements in Electrical Conductors; and I do hereby declare that the following is a full, clear, and exact description of the invention, which will enable others skilled in the art to which it appertains to make and use the same, reference being had to the accompanying drawings, which form a part of this specification, and in which—

Figure 1 is a perspective view of a short piece of my improved conductor. Fig. 2 is a side view of the same; and Fig. 3 is a transverse sectional view of my improved conductor on line $\alpha\alpha$ in Fig. 2, on an enlarged scale.

Like letters of reference designate corresponding parts in all the figures.

This invention relates to conductors for electrical currents of all kinds where it is of importance to overcome induction; and it consists in an improved antiinductive wire of the construction which will be hereinafter more fully described and claimed.

Referring to the drawings, the letter A denotes the body of a metal conductor or wire of any desired metal and dimensions according to the purpose for which it is to be used. The outside of this conductor or wire is grooved spirally in two opposite directions—that is to say, it has one or more “right-hand” spiral groove or grooves a , encircling the wire from end to end, and another “left-hand” spiral groove or series of grooves b , also extending from one end of the wire to the other, so as to intersect or cut across the spirals a at each twist or turn, as clearly illustrated on the drawings. Both of these intersecting spiral grooves or series of grooves a and b are preferably of the same depth and pitch, and may be produced by suitable machines, either by indenting the body of the wire A or by cutting out a portion of the metal on the surface. I have, however, constructed and prefer to use a machine intended specifically for the cross-grooving of the wire in such a

manner as to attain the best and most satisfactory results, which will form the subject 50 of a separate application.

I am aware that an antiinductive conductor for telegraph and telephone lines, consisting of a wire grooved spirally in one direction is not new, I, myself, being the inventor 55 and patentee of such a device as described and claimed in my Letters Patent of the United States No. 290,769, bearing date of December 25, 1883; but I have found by a long and exhaustive series of tests and experiments that while the in one direction spiraled device is a great improvement upon the ordinary plain wire usually employed for telegraph and telephone lines my improved cross-spiraled conductor possesses still greater 65 advantages as an antiinductive device, and may be used in telegraph and telephone lines in systems and under conditions (due, for example, to the proximity of electric-light wires or trolley-wires carrying high-tension currents) where an ordinary wire would be rendered utterly useless.

I desire it to be understood that this improvement is not limited in its application to wires for telegraph and telephone lines, 75 but may be advantageously introduced and adopted for electrical conductors generally; hence

What I claim as my invention, and desire to secure by Letters Patent of the United 80 States, is—

As an improved article of manufacture, an anti-inductive conductor for electric currents consisting of a wire grooved spirally in opposite directions, so that the spirals will intersect or cut across one another at each turn or twist around the wire; substantially as set forth.

In testimony that I claim the foregoing as my own I have hereunto affixed my signature 90 in presence of two witnesses.

GORHAM GRAY.
